UNITED STATES PATENT OFFICE.

THOMAS E. PRAY AND GEORGE BODIN, OF CHICAGO, ILLINOIS, ASSIGNORS TO GOODMAN MANUFACTURING COMPANY, OF CHICAGO, ILLINOIS, A CORPORATION OF ILLINOIS.

MINING MACHINE.

Application filed May 1, 1920, Serial No. 378,092. Renewed February 10, 1926.

This invention relates to coal mining machines, and more particularly to mining machines of the chain cutter type commonly known as the continuous cutter coal mining machine which is moved laterally along the wall of the mine to cut a horizontal kerf thereunder, and is particularly adapted for use in the room and pillar system of mining.

The principal object of this invention is to provide a new and improved machine of the above description which is capable of use in narrow or thin veins of coal. Further objects will hereinafter appear in the description of the construction and operation of the machine embodying our invention.

One of the principal features of the present invention relates to the construction wherein the machine is provided with a recess in the forward portion thereof into which the cuttings are brought by the cutting chain, which recess is closed to the advance side of the machine, and through which the cuttings are moved by the cutter chain to the opposite, or "following" side of the machine and are ejected therefrom. We also provide an improved operating mechanism as will hereinafter appear.

The invention consists in the combination, construction, and arrangement of parts as will hereinafter be described in connection with the accompanying drawings, and more particularly defined in these appended claims.

In the drawings, Figure 1 is a plan view of the machine in cutting position adjacent a mine wall.

Figure 2 is an enlarged side view of the machine showing details of the driving mechanism in section, and with the cutter bar broken away.

Figure 3 is a view in section of the cutter bar, and showing the front of the machine in elevation.

Figure 4 is a cross section taken on line 4-4 of Figure 3.

Figure 5 is a side view of the machine with the cutter bar removed, and illustrating details of the control mechanism.

With reference to the drawings, the mining machine comprises a main frame 1, and a cutter bar 2 of any approved construction provided with a cutter chain 3 carrying a plurality of chain blocks 4, 4, pro-

vided with cutter bits 5, 5 projecting at varying angles from said cutter bar. The main frame 1 of the machine comprises a motor 6, mounted in a casing 7, preferably located at the rear end of the machine, and a housing 8, at the front end of the machine. In order to reduce the overall height of the machine to a minimum, we construct the motor casing 7 so as to require a minimum overall height commensurate with the size of the motor having sufficient power for operating the machine. The armature of the motor is preferably arranged longitudinally of the machine, as shown in dotted lines in Figures 1 and 2. It will be seen that the height of the housing 8 which contains the driving mechanism is controlled by the height of the motor casing 7. Said motor casing is detachably connected with the housing 8 by any suitable means such as bolts 9, 9. The casing 7 and housing 8 form the base plate upon which the machine rests on the mine floor.

Machines of the class described are fed to the work by means of a flexible draft device, including a cable, chain, or the like. In the machine illustrated, we have shown a flexible cable 10, which is led around a sheave 11 at the front end of the housing 7, and is anchored near the mine wall at a point toward which the machine is to be moved. The cable 10 is wound on a motor-driven drum 12 mounted on the left side of the machine. The driving mechanism for said drum will be hereinafter described. By means of the flexible draft gear, arranged as shown, the entire machine is dragged bodily along the face, or wall, of the mine so as to perform the cutting operation in the usual manner. A retarding device is also provided to maintain the machine in its proper cutting relation to the wall. For this purpose we have shown a friction controlled drum 13 at the rear end of the motor casing carrying a flexible cable 14, which is adapted to be anchored in the direction opposite to that of the feed rope 10, and to be unwound from said drum against friction as the machine advances. It will be understood, however, that any other suitable draft device or propelling mechanism may be used for the purpose of moving and controlling the machine during the cutting operation.

Referring now more particularly to the

novel features of the invention, it will be seen in Figure 1 that the cutter bar 2 is supported by a forwardly extending lug 15 on the front end of the housing 8.

5 A recess 17 is formed underneath the housing 8, and opening to one side thereof, as shown. Said recess is provided with a bottom wall or base plate 20, which wall is a continuation of the face upon which the entire machine rests, and extends laterally under the rear end of the cutter bar. Said lower wall is provided with a boss 18, forming a lower bearing for a cutter chain driving sprocket 16, and a vertical web 15^a, adjacent said boss, which web connects the supporting lug 15 with the forward edge of wall 20, and provides a support against which the rear end of the cutter bar abuts. The cutter chain 3 is mounted on said cutter bar, and passes rearwardly around the driving sprocket. The driving mechanism for said sprocket will be hereinafter described. As the machine proceeds to the left along the mine wall, the cutter bits 5, 5 move in the direction indicated by the arrow around the cutter bar 2, thru the opening 21, into the recess 17, and around the driving sprocket 16. The cuttings are brought rearwardly from the kerf by the cutter chain, and tend to accumulate in the recess 17, as they are dislodged from the chain.

Referring now to the means for discharging the cuttings from the recess 17, which means are shown in detail in Figures 3, 4 and 5, it will be seen that the recess 17 opens to one side of the machine and forms a discharge passage 22 for the cuttings. The boundaries of the recess 17 comprise a top wall 19, bottom wall 20, and a side wall 23, all of said walls being preferably cast integral with the housing 8. The side wall 23 of the recess comprises a slightly flared portion 24 adjacent the front passage 21, an arcuate portion 25, rearwardly of said flared portion, and formed on a radius approximately concentric with the axis of the sprocket 16, and an approximately straight portion 26, which merges into said curved portion and is inclined rearwardly and toward the discharge passage 22 (see Figure 4).

55 A rib 27 projects upwardly from the base plate 20, and extends from the boss 18 outwardly and slightly rearwardly, to the margin of said base plate, as shown. An oppositely disposed rib 28 may also be provided in the upper wall 19 of the recess, if desired. Said rib is preferably arranged so as to meet the boss 18 at a tangent, and may be approximately parallel with the straight portion 26 of the side wall, or diverge slightly away therefrom toward the front of the machine, as shown in Figure 4.

60 The essential feature of the construction just described is the arrangement whereby

the cuttings are discharged from the recess by the movement of the cutter chain. This is accomplished by the novel shape, or conformation of the walls of the recess above described, in the following manner: 70 As the cuttings accumulate on the floor and along the walls of the recess 17, to a depth sufficient to come into contact with the cutter chain, they are carried by the chain blocks 4, 4 and cutting bits 5, 5, in the direction of movement of the chain. The cuttings in the portion of the recess restricted by the arcuate wall 25 are carried around by the blocks until they reach the flared portion opposite the wall 26, which flared portion is less restricted than the arcuate port 25, so that the cuttings are thrown tangentially away from the chain and are thus deflected toward the discharge passage 22. The rapid movement of the cutter chain is 85 usually sufficient to throw the cuttings beyond the side margin of the bottom wall, where they are deposited on the mine floor adjacent the discharge passage 22, and are left behind as the machine advances laterally in its cutting operation. The lateral margin of the lower wall 20 is substantially in longitudinal alignment with the portion of the cutter chain on the following side of the cutter bar, so that excessive accumulations of cuttings adjacent the discharge passage may be readily cleared away by the operator or his helper, in the usual manner. The provision of the oppositely disposed ribs 27, 28 serves to assist in directing the movement of the cuttings toward the discharge passage.

90 The driving mechanism comprises a horizontal shaft 29 carried by suitable bearings 30, 31 and 32 in the housing 8; said shaft having a gear 33 meshing with the motor pinion 34 and arranged with its axis above, and to one side of the axis of the motor 6.

95 The driving connection for the feed rope drum 12 comprises a worm 35 carried by the shaft 29, and engaging a worm wheel 36 mounted on a longitudinal shaft 37, and having operative connection with the feed drum 12 thru a suitable planetary change speed mechanism 38, shaft 39 and gears 40 and 41. The planetary mechanism is operated by a longitudinally movable shaft 29^a extending through shaft 37 to a clutch member 38^a in the planetary mechanism and provided with a shifter arm 29^b, carried by a 100 vertically disposed shaft 29^c extending upwardly thru the housing 8. A control lever 29^d (see Figure 5) is attached to said shaft, and extends rearwardly so as to be manipulated from the rear of the machine.

105 The driving connection for the cutter chain sprocket 16 comprises a bevel pinion 42 on the forward end of the shaft 29, and meshed with the bevel gear 43, carried by a 110 pin 44. Said pin is 115

mounted at its upper end in a yoke 45 rigidly attached to the side walls 46, 46 of the housing 8. This pin extends downwardly thru the top wall 19 of the recess 17, and is mounted at its lower end in the boss on the lower wall 20. The bevel gear 43 comprises a toothed periphery 46, and a downwardly extending neck portion 47, and is provided with a suitable bearing sleeve 48 on the pin 44. The chain sprocket 16 is mounted at the lower end and outside of the hub portion 47 just described, and is provided with a bearing sleeve 49. Connecting sleeve 50 is also mounted on said bearing sleeve 49 above the chain sprocket 16 and in clutched engagement with the latter, so as to allow the sprocket to be easily taken out and replaced.

The mechanism for clutching the bevel gear 43 to the driving sprocket 16 comprises a vertically movable clutch sleeve 51 provided with a suitable yoke 52, and having downwardly extending clutch fingers 54, 54 extending thru suitable openings 55, 55 in the beveled gear 43, and adapted to have clutching engagement with recesses 56, 56, carried by the connecting sleeve 50 engaged with the sprocket 16 as described. The clutch sleeve 51 is provided with a bearing sleeve 57, and is adapted to revolve with the gear 43. In the position shown in Figure 2, the clutch is disengaged, that is to say, it is raised in its uppermost position so that the clutch fingers 54, 54, are out of engagement with the recesses 56, 56, carried by the connecting sleeve 50. The clutch is manipulated by means of a shifter arm 58 (see Figure 1) carried by a rocking shaft 59 mounted on the bearing 60. The control connection for the clutch comprises segmental gears 61 and 62 and a rocking shaft 63 extending to the rear of the machine, and manipulated by handle 64 (see Figure 1). Thrust bearing plates 65, 65 are provided for the bevel gear 43. Similarly, the shaft 29 is provided with a thrust collar 66 and thrust bearing 67.

A removable top or cover plate 70 is provided to cover the housing 8.

From the foregoing description, it will be seen that we have provided a coal cutting machine which may be moved laterally and in which the cuttings are carried into the recess 17, and ejected from the side of the machine opposite to that in which the entire machine is moved during the cutting operation. Said recess is closed to the advance side of the machine so that no cuttings can get into the path of movement of the machine. The lower wall 20, in addition to forming a portion of the base plate upon which the machine rests, also prevents the cuttings from lodging under the forward end of the machine. The motor and motor casing are mounted at the rear end of the

machine, and rest on the mine floor, while the operating mechanism, including the draft gearing and cutting mechanism, is located at the front end of the machine. The longitudinal shaft 29 is positioned above the axis of the motor pinion 34 so as to pass above, and have driving connection with the transverse shaft for the draft gearing, and also has driving connection with the bevel gear 43 located in the forward end of the motor housing over the recess 17 for driving the cutter chain sprocket 16. This arrangement of parts provides a novel and compact construction in which the overall height of the entire mechanism may be reduced to a minimum so that the machine may be used in narrow or thin veins of coal.

Another advantage of this construction is the provision of the yoke 45 which forms an upper bearing for the pin 44 independent of the movable top 70 of the housing 8. This arrangement allows the mechanism to be operated while the top is removed.

Another advantage of this invention is the arrangement of the control levers extending to the rear of the machine so as to be easily accessible for the operator while the machine is in operation.

Having described our invention what we claim as new and desire to cover by Letters Patent, is:

1. In a mining machine adapted to be moved laterally along the face of a mine wall, the combination of a frame having a passageway opening to the front end and communicating with a discharge passage opening to the side of the machine opposite to the direction in which the machine is adapted to move, an endless cutting element extending from the end of said frame and adapted to move cuttings into said passageway, and an arcuate deflector in said passageway adapted to coat with said cutter chain for directing the movement of the cuttings toward said discharge passage.

2. In a mining machine adapted to be moved laterally along the face of a mine wall, the combination of a frame having a passageway closed to the advance side of said machine, but opening to the front end and communicating with a discharge passage opening to the following side of the machine, an endless cutting element extending from the front end of said frame and adapted to move the cuttings into said passageway, and a deflector in said recess forming a restricted portion of said passageway for directing the movement of the cuttings toward said discharge passage.

3. In a mining machine adapted to be moved laterally along the face of a mine wall, the combination of a frame having a recess in the front portion thereof, closed to the advance side of said frame and forming a discharge passage opening to the side of

the machine opposite to the direction in which the machine is adapted to move, a supporting member mounted in said recess, a movable cutter chain carried by said supporting member, and a deflector in said recess having a rearwardly extending portion thereof forming a relatively restricted passageway between said cutter chain and said deflector, and having a second portion thereof of forming a relatively large passageway communicating with said discharge passage.

4. In a mining machine adapted to be moved laterally along the face of a mine wall, the combination of a motor having a horizontally disposed driving shaft, a casing for said motor adapted to rest on the mine floor, a frame located forwardly of said motor, a cutter bar extending from the forward end of said frame and provided with a cutter chain, a longitudinal shaft mounted in said frame having its axis above the axis of said driving shaft and having driving connection therewith, a vertically disposed gear member mounted forwardly of said longitudinal shaft, and a sprocket having operative connection with said gear member, and adapted to drive said cutter chain.

5. In a mining machine adapted to be moved laterally along the face of a mine wall, the combination of a motor having a horizontally disposed driving shaft, a casing for said motor adapted to rest on the mine floor, a frame located forwardly of said motor provided with a cutter bar extending longitudinally from its forward end, a longitudinally extending shaft carried by said frame above the axis of said driving shaft, and having driving connection therewith, draft mechanism carried by said frame including a transverse horizontally disposed shaft having operative connection with said longitudinal shaft, a cutter chain supported by said cutter bar, and means for driving said cutter chain comprising a vertically disposed gear member mounted forwardly of said longitudinal shaft, and a sprocket having driving connection therewith.

6. In a mining machine adapted to be moved laterally along the face of a mine wall, the combination of a motor, a casing for said motor adapted to rest on the mine floor, a housing located forwardly of said motor having a recess in its forward portion, a cutter bar extending forwardly from the forward end of said housing and provided with a cutter chain, a longitudinal shaft mounted in said housing having its axis above the axis of said motor and having driving connection therewith, a worm carried by said longitudinal shaft, a transverse shaft having a worm gear meshed with said worm, draft mechanism on one side of said housing having operative connection with said transverse shaft, a vertically disposed gear member mounted forwardly of said lon-

gitudinal shaft, and a sprocket in said recess having operative connection with said gear member, and adapted to drive said cutter chain.

7. In a mining machine adapted to be moved laterally along the face of a mine wall, the combination of a motor, a casing for said motor adapted to rest on the mine floor, a housing located forwardly of said motor provided with a cutter bar extending longitudinally from its forward end, a cover for said housing, a longitudinally extending shaft carried by said housing above the axis of said motor, and having driving connection therewith, draft mechanism carried by said housing including a transverse horizontally disposed shaft having operative connection with said longitudinal shaft, a cutter chain supported by said cutter bar, and means for driving said cutter chain comprising a gear member mounted forwardly of said longitudinal shaft, and independent of said housing cover, and a sprocket having driving connection with said gear member.

8. In a mining machine, the combination of an elongated frame having a recess in the forward end thereof provided with top and bottom walls, and opening to the forward end and to one side of said frame, and an endless cutting element supported by said frame adapted to move thru said recess and to coat with the walls thereof to discharge the cuttings to one side of the machine, a motor, and a casing for said motor adapted to rest on the mine floor.

9. In a mining machine adapted to be moved laterally along the face of a mine wall, the combination of an elongated frame having a recess in the forward end thereof provided with a top, bottom, rear, and one side wall, whereby said recess opens to the front and one side of said frame, and a cutting element extending longitudinally from, and supported by, said frame, adapted to contact with said walls to discharge the cuttings to one side of the machine.

10. In a mining machine adapted to be moved laterally along the face of a mine wall, the combination of a frame having a recess at the front end thereof, provided with a top, bottom, rear and one side wall, whereby said recess opens to the front end and to the side opposite the direction in which the machine is moved, a support in said recess, a cutting element adapted to move into the front end of said recess and to change its direction of movement toward the open side of said recess about said support, said side and rear walls of said recess forming a continuous arcuate surface conforming substantially with the initial change of direction of said cutting element.

11. In a mining machine adapted to move laterally along the face of a mine wall, the combination of a frame having a recess in

the forward end thereof, a cutting element adapted to move through said recess and means in said recess restraining the cuttings from being discharged on the advance side of the machine, and cooperating with said cutting element for discharging the cuttings from the following side of said machine, a motor, and a casing for said motor mounted rearwardly of said frame and forming therewith the bottom plate of said machine on which the machine rests on the mine floor.

12. In a room and pillar mining machine, the combination of a frame having draft means operable on opposite ends of the frame for advancing the machine laterally along a mine wall, a cutting element rigidly supported on said frame and provided with a movable cutter chain extending rearwardly through a passageway extending longitudinally and thence transversely toward the following side of said frame, the side walls of said passageway cooperating with said cutter chain to move the cuttings rearwardly and then laterally to be discharged at the following side of the machine.

13. In a mining machine, the combination of a frame, means for advancing the machine laterally along the mine wall, a movable cutting element supported by said frame and extending into a recess in the forward portion thereof, a deflector in said recess adapted to cooperate with said cutting element to discharge the cuttings to the following side of said machine, a motor, and a

casing for said motor mounted rearwardly 35 of said recess and adapted to rest on the mine floor.

14. In a mining machine, the combination of an elongated frame having a cuttings discharge channel in the forward end thereof 40 opening to one side of said frame, an endless cutting element supported by said frame and having its rear end disposed in said channel, a motor, driving connections for said cutter chain, and feed operating means 45 to move said mining machine laterally on its bottom along a mine floor, said feed means including a planetary gearing having a portion thereof extending below the upper boundary and to one side of said cuttings 50 channel.

15. In a mining machine, the combination of an elongated frame having a cuttings discharge channel in the forward end thereof 55 opening to one side of said frame, an endless cutting element supported by said frame and having its rear end disposed in said channel, a motor, driving connections for said cutter chain, and feed operating means to move said mining machine laterally on its 60 bottom along a mine floor, said feed means comprising a planetary gearing mechanism disposed on a transverse axis having a portion thereof extending below the upper boundary and on the closed side of said cut- 65 tings channel.

THOMAS E. PRAY.
GEORGE BODIN.

DISCLAIMER.

1,600,245.—*Thomas E. Pray and George Bodin, Chicago, Ill. MINING MACHINE.*
Patent dated September 21, 1926. Disclaimer filed January 29, 1927, by the
patentees, assignee *Goodman Manufacturing Company*, consenting.

Hereby enter this disclaimer to that part of the subject matter claimed in said
specification as set forth in claims numbered 14 and 15, which are in the following
words:

“14. In a mining machine, the combination of an elongated frame having a cut-
tings discharge channel in the forward end thereof opening to one side of said
frame, an endless cutting element supported by said frame and having its rear
end disposed in said channel, a motor, driving connections for said cutter chain, and
feed operating means to move said mining machine laterally on its bottom along a
mine floor, said feed means including a planetary gearing having a portion thereof
extending below the upper boundary and to one side of said cuttings channel.

“15. In a mining machine, the combination of an elongated frame having a cut-
tings discharge channel in the forward end thereof opening to one side of said
frame, an endless cutting element supported by said frame and having its rear
end disposed in said channel, a motor, driving connections for said cutter chain,
and feed operating means to move said mining machine laterally on its bottom
along the mine floor, said feed means comprising a planetary gearing mechanism
disposed on a transverse axis having a portion thereof extending below the upper
boundary and on the closed side of said cuttings channel.”

[*Official Gazette February 8, 1927.*]
